MECHANICAL DIALYZER

Alfred Henley, Takoma Park, Md., assignor to
American Instrument Company, Inc., Silver
Spring, Md.

Application January 8, 1951, Serial No. 204,984

11 Claims. (Cl. 210—8.5)

1 This invention relates to biological laboratory equipment, and more particularly to apparatus for the dialysis of protein and other solutions.

A main object of the invention is to provide a novel and improved apparatus for dialyzing protein and other solutions, such as blood serum or the like, said apparatus being simple in construction, being easy to manipulate, and greatly reducing the time required for dialysis, as over previously known apparatus.

A further object of the invention is to provide an improved mechanical dialyzing apparatus for use in equilibrating protein or other solutions against a suitable buffer mixture prior to study of the solution in electrophoresis or similar apparatus, the improved dialyzing apparatus involving relatively inexpensive parts, being sturdy in construction, and being compact in size.

A still further object of the invention is to provide an improved mechanical dialyzer for use in preparing protein and other solutions for study in electrophoresis or similar apparatus, said dialyzer providing reduction of the time required for equilibration of the solution under study to a minimum, employing very simple components, being readily assembled, and requiring a minimum degree of manufacturing precision in fabricating the various parts thereof.

Further objects and advantages of the invention will become apparent from the following description and claims, and from the accompanying drawings, wherein:

Figure 1 is a vertical cross-sectional view taken through an improved mechanical dialyzer constructed in accordance with the present invention.

Figure 2 is a top plan view of the mechanical dialyzer of Figure 1.

Figure 3 is an enlarged fragmentary cross-sectional detail view taken on line 3—3 of Figure 1.

Figure 4 is a fragmentary cross-sectional detail view taken on line 4—4 of Figure 3.

Figure 5 is a fragmentary vertical cross-sectional view taken through a modified form of mechanical dialyzer according to the present invention, said view being taken on line 5—5 of Figure 6.

Figure 6 is a top plan view of the mechanical dialyzer of Figure 5.

Figure 7 is a cross-sectional detail view taken on line 7—7 of Figure 5.

Blood serum and other biological systems containing proteins as well as low-molecular, diffusible ions and organic compounds must be

2 equilibrated against a suitable buffer mixture prior to study in electrophoresis apparatus. By establishing equilibrium between the colloid and the supernatant solution, boundary anomalies due to pH and conductivity difference are eliminated to a certain extent. At present it is standard procedure to dialyze the protein solution against a large volume of buffer through cellophane or similar permeable membrane tubing at low temperature and for a considerable period of time. For example, in electrophoresis experiments on normal and pathological human blood serum and plasma, where static dialysis at 0° to 2° centigrade has been employed, the process has required three days, the outside buffer solution being changed every day. An alternative procedure has been to rotate the buffer solution for one hour at room temperature, replacing it by fresh buffer, and allowing dialysis to proceed for 24 hours or more at 0° to 2° centigrade.

For a further discussion of the electrophoresis apparatus and method, reference is made to U. S. Patent 2,495,297 to Kurt G. Stern, issued January 24, 1950. In said patent an example of the above dialysis process, as a preliminary step in performing an electrophoresis experiment, is fully described.

In clinical work, the time required for the equilibration process represents a factor of major importance, since it delays appreciably the examination of the serum or plasma in the electrophoresis apparatus, and hence the availability of the results to the medical personnel involved.

A main purpose of the present invention is therefore to provide an apparatus wherein the time course of dialysis may be reduced to a minimum compatible with the requirements of precise electrophoresis experiments.

Referring now to the drawings, and more particularly to Figures 1 to 4, the mechanical dialyzing apparatus may comprise a glass receptacle 11 provided with a removable, peripherally flanged top cover 12. Secured on the top cover 12 is a stirrer motor 13 whose shaft 14 extends rotatably through the center of the cover 12. Shaft 14 is formed with a depending axial stud 15 to which is secured a collar member 16, as by a set screw 17 provided in the upper portion of said collar member. As shown, the collar 16 has a reduced lower portion 18, and frictionally engaged on said reduced lower portion is a sleeve 19 of rubber or similar elastic deformable material. Frictionally secured in the lower portion

of sleeve 19 is the shaft 20 of a helically twisted stirrer rod 21.

Secured to the under surface of cover 12 coaxially with the shaft 14 is a depending, downwardly tapering, rigid conical shell member 22, which extends a short distance below the end of sleeve 19 and which is open at its lower end. The inside diameter of said lower end is substantially greater than the outside diameter of the sleeve 19, whereby the sleeve member is free to flex to a substantial degree inside said shell member, as when the stirrer rod 21 deviates from a vertical position.

The shell member 22 is formed at the lower portion of its outer surface with an annular groove 23. Designated at 24 is the dialyzing membrane, which is in the form of a bag of suitable, thin, semi-permeable material, such as cellophane, or the like. A typical material may be Visking sausage casing. The upper portion of the bag 24 is engaged over the lower end of the shell member 22, as shown, and is sealingly clamped thereto by a rubber ring 25 arranged to force an annular portion of the bag 24 into groove 23.

It will be noted that in order to secure the bag to the shell member, it is merely necessary to engage the bag on the lower portion of the shell member and then roll the ring 25 upwardly along the bag until the ring slips into the annular groove 23, the ring being stretched by the upwardly flaring configuration of the shell member and hence exerting a tight sealing and clamping action on the bag in cooperation with the groove 23. It will be further noted that the bag may be readily detached from the shell member 22 by exerting downward force on the ring 25, whereby said ring is disengaged from the groove 23.

Designated at 26 is a relatively heavy, rigid ring or collar, which is disposed in the bottom of the bag 24. Ring 26 performs a double function: it prevents the lower portion of the bag from collapsing and it weights the bag so that it remains relatively stationary while the stirrer rod 21 is revolving and oscillating.

In operation, the liquid to be dialyzed is placed in the bag 24 and the bag is secured to the shell member 22 as above described. The buffer solution is placed in the receptacle 11 and the cover 12 is then placed on the top rim of said receptacle. The motor 13 drives the shaft 14 at a relatively slow speed, suitable speed-reducing means being incorporated in said motor. Torque is transmitted to the helical stirrer rod 21 through the flexible sleeve 19. Due to the yieldability of the connecting sleeve 19, the stirrer 21 revolves the liquid in bag 24 gently in the bag and at a relatively slow rate. The reaction of the liquid causes the stirrer to be deviated from a vertical position instead of producing turbulence in the liquid. Since turbulence is minimized, dialysis is allowed to proceed substantially under the same external physical conditions prevailing if the liquid in the bag were stationary relative to the inside surface of the bag, but the rate of dialysis is greatly accelerated since many more molecules or ions in the liquid are brought into contact with the semi-permeable membrane of the bag in a given period of time than if the natural movements of said molecules or ions were alone relied on for dialysis.

Secured to the top cover 12 are a pair of upstanding support legs 27, 27' whose top ends are flush with the top surface of motor 13 and which are spaced so as to define tripod elements in conjunction with the motor for supporting the cover

in an inverted horizontal position when the cover is removed from the receptacle 11.

In the modified form of the invention shown in Figures 5, 6 and 7, the bag 24 is sealingly clamped to the depending conical shell member, shown at 22, by a rigid clamping ring 28, which is provided with diametrically opposed apertured lug portions 29, 29'. The upstanding tripod legs, shown at 27', 27' are arranged diametrically opposite each other with respect to the motor shaft 14. The lower portions of legs 27', 27' comprise depending threaded stud elements 30, 30 which extend through cover 12 and are secured thereto by nuts 31, 31. The stud elements 30, 30 extend through the respective apertured lug portions 29, 29' and are provided below said lug portions with knurled nuts 32, 32 which exert upward force on the ring member 28, and cause said ring member to sealingly clamp the rim portion of bag 24 to the shell member 22.

In the arrangement of Figures 5, 6 and 7, it is not necessary to provide an annular groove in the external surface of the shell member, and the size of the aperture in the ring member 28 is not critical, since the tapering configuration of the shell member provides clamping engagement of the ring member therewith regardless of variations in size of said aperture.

Although certain specific embodiments of improved mechanical dialyzers have been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. A mechanical dialyzer comprising a receptacle, a top cover removably mounted on said receptacle, a motor mounted on said cover, a depending shaft element coupled to said motor and extending through said cover, a depending stirrer, elastic deformable means resiliently connecting said stirrer to said shaft element, and a bag of permeable membrane material secured to said cover around said stirrer.

2. A mechanical dialyzer comprising a closed receptacle, a vertical shaft element extending rotatably through the top wall of the receptacle, a stirrer rod, elastic deformable means resiliently connecting said stirrer rod to said shaft element, and a bag of permeable membrane material secured to said top wall around said stirrer rod.

3. A mechanical dialyzer comprising a closed receptacle, a vertical shaft element extending rotatably through the top wall of the receptacle, an annular shell depending from said top wall around the shaft element, a depending stirrer rod, elastic deformable means resiliently connecting said stirrer rod to said shaft element inside said shell, said stirrer rod depending through the bottom rim of said shell, and a depending bag of permeable membrane material secured to said shell and surrounding said stirrer rod.

4. A mechanical dialyzer comprising a closed receptacle, a vertical shaft element extending rotatably through the top wall of the receptacle, a rigid annular shell depending from said top wall around the shaft element, a depending sleeve member of elastic deformable material secured to said shaft element, a depending stirrer rod secured to said sleeve member, whereby the stirrer rod is resiliently connected to said shaft element, said stirrer rod depending through the bottom rim of said shell, and a depending bag of per-

meable membrane material secured to said shell and surrounding said stirrer rod.

5. A mechanical dialyzer comprising a closed receptacle, a vertical shaft element extending rotatably through the top wall of the receptacle, a rigid annular shell depending from said top wall around the shaft element, a depending sleeve member of elastic deformable material secured to said shaft element, a depending stirrer rod secured to said sleeve member, whereby the stirrer rod is resiliently connected to said shaft element, said stirrer rod depending through the bottom rim of said shell, a depending bag of permeable membrane material secured to said shell and surrounding said stirrer rod, and a rigid, relatively heavy spreader member horizontally disposed in the bottom of said bag.

6. A mechanical dialyzer comprising a closed receptacle, a vertical shaft element extending rotatably through the top wall of the receptacle, a stirrer rod, elastic deformable means resiliently connecting said stirrer rod to said shaft element, a bag of permeable membrane material secured to said top wall around said stirrer rod, and a rigid, relatively heavy spreader member horizontally disposed in the bottom of said bag.

7. A mechanical dialyzer comprising a closed receptacle, a vertical shaft element extending rotatably through the top wall of the receptacle, a rigid, downwardly tapering, annular shell depending from said top wall around the shaft element, the outer surface of said shell being formed with a peripheral groove, a depending stirrer rod, elastic deformable means resiliently connecting said stirrer rod to said shaft element, said stirrer rod depending through the bottom rim of said shell, a depending bag of permeable membrane material engaged on the shell and surrounding the stirrer rod, and a securing ring of elastic material engaged over the upper portion of the bag adjacent the groove in said shell and urging said portion into the groove, whereby the bag is clamped to the shell.

8. A mechanical dialyzer comprising a closed receptacle, a vertical shaft element extending rotatably through the top wall of the receptacle, a rigid, downwardly tapering, annular shell depending from said top wall around the shaft element, the outer surface of said shell being formed with a peripheral groove, a depending stirrer rod, elastic deformable means resiliently connecting said stirrer rod to said shaft element inside said shell, said stirrer rod depending through the bottom rim of said shell, a depending bag of permeable membrane material engaged on the shell and surrounding the stirrer rod, and a securing ring of elastic material engaged over the upper portion of the bag adjacent the groove in said shell and urging said portion into the groove, whereby the bag is clamped to the shell.

9. A mechanical dialyzer comprising a closed receptacle, a vertical shaft element extending rotatably through the top wall of the receptacle, a rigid, downwardly tapering, annular shell depending from said top wall around the shaft element, a depending stirrer rod, elastic deformable means resiliently connecting said stirrer rod to said shaft element, said stirrer rod extending through the bottom rim of said shell, a depending bag of permeable membrane material engaged on the shell and surrounding the stirrer rod, a rigid clamping ring engaged over the upper portion of the bag around said shell, and means connecting said clamping ring to said top wall and arranged to exert upward force on said clamping ring, whereby the bag is sealingly locked to the shell.

10. A mechanical dialyzer comprising a closed receptacle, a vertical shaft element extending rotatably through the top wall of the receptacle, a rigid, downwardly tapering, annular shell depending from said top wall around the shaft element, a depending stirrer rod extending through the bottom rim of said shell, elastic deformable means resiliently connecting said stirrer rod to said shaft element, a depending bag of permeable membrane material engaged on the shell and surrounding the stirrer rod, a rigid clamping ring engaged over the upper portion of the bag around said shell, and means connecting said clamping ring to said top wall and arranged to exert upward force on said clamping ring, whereby the bag is sealingly locked to the shell.

11. A mechanical dialyzer comprising a closed receptacle, a vertical shaft element extending rotatably through the top wall of the receptacle, a rigid, downwardly tapering, annular shell depending from said top wall around the shaft element, the outer surface of said shell being formed with a peripheral groove, a depending stirrer rod extending through the bottom rim of said shell, elastic deformable means resiliently connecting said stirrer rod to the shaft element, a depending bag of permeable membrane material engaged on the shell and surrounding the stirrer rod, and a securing ring of elastic material engaged over the upper portion of the bag adjacent the groove in said shell and urging said portion into the groove, whereby the bag is clamped to the shell.
